UNITED STATES PATENT OFFICE.

ARTHUR J. AYLESWORTH, OF LAKESIDE, MICHIGAN.

FAN.

Application filed March 7, 1921. Serial No. 450,153.

To all whom it may concern:

Be it known that I, ARTHUR J. AYLESWORTH, citizen of the United States, residing at Lakeside, in the county of Berrien 5 and State of Michigan, have invented a certain new and useful Improvement in Fans, of which the following is a full, clear, concise, and exact description.

My invention relates to hand operated 10 devices in which reciprocating movement is translated into rotary movement, the invention being of particular utility in the construction of hand operated fans, though it is not to be limited to such use.

15 The device of my invention includes a reciprocable gear actuating element which is manually operable in one direction, when employed in a hand operated device and is preferably given restoring movement by 20 means of a light spring. There is a guide for confining this gear actuating element to its line of travel and this guide is preferably tubular to constitute it also a housing for the gearing and a handle by which the 25 entire device may be held. The load shaft is desirably co-axial with said tubular housing which carries suitable bearings for it.

The gear element that is actuated by the aforesaid reciprocable gear actuating element 30 preferably surrounds the load shaft on which it is loose and is capable of limited movement longitudinally thereof. This gear element is formed to have a spiral thread that is engaged by the reciprocable 35 gear actuating element when this actuating element is moved in one direction, by hand in the preferred embodiment of the invention, the gear element engaged thereby being brought into driving engagement or connection with the load shaft that it thereafter rotates. When the gear actuating 40 hand pressure upon the gear actuating element is released at the conclusion of or at any point in the travel of this actuating element, said gear element is disengaged from 45 the load shaft by the action of the light spring which then is also preferably effective to place the gear actuating element at one limit of its travel. If the load upon 50 the shaft happens to be in the form of fan blades, they may be folded to lie along their aixs of rotation, whereafter they may be drawn into the tubular housing or handle.

55 The invention will be more fully explained by reference to the accompanying drawings showing the preferred embodiment

thereof and in which Fig. 1 is a longitudinal sectional elevation of a fan structure embracing the invention, the fan blades being shown unfolded; Fig. 2 is a view of the 60 parts shown in Fig. 1 with the blades drawn into the hollow handle; Fig. 3 is a view in elevation, partially broken away, of the structure adjusted as illustrated in Fig. 2; Fig. 4 is an end view; and Figs. 5 and 6 are 65 sectional views respectively taken on lines 5-5 and 6-6 of Fig. 2.

Like parts are indicated by similar characters of reference throughout the different figures.

As illustrated, the load shaft 1 is journaled at its ends upon bearings 2 and 3 that are at the opposite ends of a tubular shell 4.

The bearing 3 is preferably a ring in the 75 outer end of an inner shell 5 that is securely anchored within a recess 6 in the bottom of the shell 4. The shaft has a flange 1' engaging bearing balls 3' to take up shaft thrust. Fan blades 8 are illustrated in the present embodiment of the invention as the load which is to be driven by said shaft. Each blade is curled at its inner end about the wire of a wire ring 9 that is disposed within a hollow mounting collar 10. This wire ring 9 80 is resilient and slightly expandable to permit it to be separated from the shaft with which it is coupled. The outer end of collar 10 is formed with a recess that hooks over the hinged ends of the blades 8 so that these 85 blade ends may be forced into and out of their seat 11 in the shaft head 12 to establish or break their driving connection with the shaft 1, the resilient wire ring 9 permitting the separation of the blades and shaft 90 and establishing the connection of the blades and shaft, according to the adjustment of said ring that is effected by the collar 10.

A spiral gear 13 surrounds and is loose 100 upon the load shaft and is adapted to move longitudinally of the shaft to a limited extent defined by the outer shaft ring 3 and the inner shaft flange 14. For economy 105 and simplicity of construction the spiral gear 13 is a spiral helix of stiff wire whose inner end is brought into driving engagement with the inner shaft flange 14 which is formed with recesses 15 for engagement with said inner end of the wire helix. The 110 spiral gear is movable longitudinally of the shaft to the limited extent permitted by the

ring 3 and flange 14 and is also rotated by means of the gear actuating element 16 movable longitudinally of the shaft and directly guided in its travel by slot 17 that is formed 5 longitudinally in the inner shell 5 forming a part of the handle structure and in which slot the gear actuating element slides. The gear actuating element is preferably in the form of a pin that enters the spiral space 10 defined by the wire of the spiral gear groove. This pin is carried by a cylindrical sliding block 18 that is in close sliding fit within the handle. Movement longitudinally of the handle or shell 4 is imparted to 15 the pin 16 by means of a trigger thumb piece 19 pivotally mounted upon the sliding block at 20 and passing through a guiding slot 21 formed longitudinally of and in the hollow handle 4, this slot 21 being the main 20 guiding influence of the gear actuating element.

When the gear actuating element is in fan operating adjustment the heel 22 of the trigger is engaged with the seat 23 formed 25 in the hollow sliding block 18. A light coiled spring 24 is bottomed at one end upon the inner end of the shell 4 and has its other end in thrusting relation with the gear actuating element 16 preferably 30 through the intermediation of the sliding block 18, whereby said gear actuating element is restored to the outer end of the shell 4 and the spiral gear 13 is normally maintained out of driving connection with 35 the load shaft flange 14. When the fan is to be operated, the gear actuating element 16 is manually depressed against the force of the light spring 24, being consequently moved longitudinally of the shaft to acquire 40 driving connection with the load shaft flange 14 to rotate it and its shaft as the manually effected movement of the gear actuating element continues. When the gear actuating element is released at any place to which 45 it is manually brought, the light spring 24 will operate to reverse the direction of travel thereof to restore it to idle position. In this return movement of the gear actuating element 16 the gear 13 will be thereby 50 lifted out of driving connection with the load shaft so that such shaft will not be positively rotated thereby on the spring effected return movement of said gear actuating element. This construction permits the 55 spring 24 to be very light and easily overcome by the hand pressure employed to turn the shaft. By engaging the element 19 by the thumb and the hollow 26 in the base of the tubular shell 4 by a finger the device 60 may readily be held and operated with the fan blades close to the face.

When the fan is not in use, its blades 8 may be folded or collapsed, to which end their mounting collar 10 is inwardly pressed 65 to bring the hinged ends of the blades

out of their receiving groove 11, whereafter this collar and the blades assembled therewith are drawn into the tubular shell. The trigger 19 may also be folded against the side of the handle after it is moved to the 70 base of the handle, as indicated in Fig. 2. In this folding operation of the trigger the trigger tail 27 engages the sliding block 28 and forces it inwardly against the force of the spring 24, and so warps the positions 75 of the trigger and the parts moving therewith, that they will be retained at the base of the handle.

In the embodiment of the invention illustrated a pair of claws 29 are mounted upon 80 the inner sliding hollow block 28. They pass through camways 30 in the sliding block 18, which normally hold these claws out of action. When the fan blades are to be collapsed the folding of the trigger will 85 force the rearward movement of the inner sliding block 28 that carries with it the claws 29 and causes these claws to engage the flange 31 on the collar 10, the trigger, however, being given its folding adjustment 90 when it is at the outermost end of its travel. The claws 29, being now engaged with the flange 31, will draw the collar 10 within the handle as the trigger 19 is moved rearwardly, the collar separating the hinged 95 ends of the fan blades from the recess 11 and carrying these hinged ends of the fan blades within the handle. The shaft head 12 carries a guiding formation 32 that engages the fan blades as their inner ends are moved 100 rearwardly within the hollow handle whereby the folding of the fan blades is effected so that they will be substantially entirely enclosed by the handle when the trigger has been moved to its rearmost position in which 105 it is held by the warping of the parts before described. When the fan is again put in use the trigger is put in its unfolded position shown in Fig. 1, whereupon the spring 24 will be effective to place the blocks 18 and 110 28 in their outermost position together with the trigger to enable the fan to be operated in the manner described. In this adjustment the claws 29 are disengaged from the collar 10, the hook ends thereof lying in the 115 zone that is between the flanges 31 and 33. Features not herein claimed are claimed in my divisional application Serial No. 572,111, filed June 28, 1922.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A fan structure including a rotatable fan blade foldable to lie along its axis of ro- 130

tation; manually operated mechanism for rotating the blade; and a shell constituting a handle for the fan structure and a support for the operating mechanism, said fan blade being insertable, when folded, within said shell.

2. A fan structure including a rotatable fan blade foldable to lie along its axis of rotation; manually operated mechanism for 10 rotating the blade; means for connecting the fan blade with and disconnecting it from said driving mechanism; and a shell constituting a handle for the fan structure and a support for the operating mechanism, said fan blade 15 being insertable, when folded and uncoupled, within said shell.

3. A fan structure including a rotatable fan blade foldable to lie along its axis of rotation; manually operated mechanism for 20 rotating the blade and including a shaft upon and with which the fan blade is separately coupled; means for connecting the fan blade with and disconnecting it from said driving mechanism; and a shell constituting a handle

for the fan structure and a support for the 25 operating mechanism, said fan blade being insertable, when folded and uncoupled, within said shell.

4. A fan structure including a rotatable fan blade foldable to lie along its axis of 30 rotation; manually operated mechanism for rotating the blade and including a shaft upon and with which the fan blade is separably coupled; means for connecting the fan blade with and disconnecting it from said 35 driving mechanism; a shell constituting a handle for the fan structure and a support for the operating mechanism, said fan blade being insertable, when folded and uncoupled, within said shell; and means assembled with 40 the shell and movable along the same that is coupled with the blade structure of the fan to move it within the handle.

In witness whereof, I hereunto subscribe my name this second day of March A. D., 45 1921.

ARTHUR J. AYLESWORTH.
